Application June 16, 1938, Serial No. 77,881

To all whom it may concern:

Be it known that I, Waldemar Kops, a citizen of the United States, residing in the Borough of Manhattan, county and State of New York, have invented a new, original, and ornamental Design for a Girdle, of which the following is a specification, reference being had to the accompanying drawing, forming a part thereof.

In the drawing, Figure 1 is a front view of a girdle embodying the new design, and

The characteristic feature of my design resides in the inverted V-shaped ribbing on the front-central portion of the girdle together with the contrasting upright V-shaped ribbing on the back-central portion thereof in combination with top and bottom borders of the form and in the proportion shown.

I claim:

The ornamental design for a girdle, as shown and described.
